ANTIAIRCRAFT GUN

William W. Fergus, West Newton, Pa.

Application February 28, 1934, Serial No. 713,370

5 Claims. (Cl. 89—37)

This invention relates to anti-aircraft guns and has for its object the provision of a mechanism whereby the gun may be readily trained upon approaching aircraft whether operated in daylight or at night, and a further object of the invention is to provide a simple construction whereby the gun may be disposed at various angles or set in a vertical position to be trained upon aircraft which may be traveling directly overhead or may be trained upon one side for more convenient firing at an aircraft which may be directly approaching the gun. These several objects, and other objects which will appear incidentally in the course of the following description, are attained in such 10 an apparatus as is illustrated in the accompanying drawings, and the invention resides in certain novel features which will be particularly defined in the appended claims.

In the drawings,
20 Figure 1 is a side elevation of an anti-aircraft gun embodying the present invention.

Figure 2 is a similar view, partly in section, showing the gun adjusted to be fired at a plane which is directly overhead.

25 Figure 3 is a plan view, with parts in section, of the gun as it appears in the position shown in Figure 2.

Figure 4 is a detail section of the mounting of the gun and sight bar whereby pivotal movement 30 of these elements is permitted.

Figure 5 is an enlarged detail on the line 5—5 of Figure 3.

In carrying out the present invention, there is provided a pedestal or supporting base 1 which 35 should be of substantial construction so that under all conditions it will remain steady wherever it may be placed. Preferably, the pedestal is somewhat heavy and is to be secured in a fixed location. In the particular design shown in the 40 drawings, the pedestal is tapered upwardly and is provided with a central opening through its upper end to receive a swivel stem 2 depending from a head 3 and rotatably fitted in said opening. On the lower end of the stem, a retaining nut 4, 45 or other retaining element, is mounted and is turned home against an opposing surface of the pedestal so that, while the stem and head will be firmly held upon the pedestal, they may be turned therein to bring the gun, mounted on the head, 50 into any desired position in a horizontal plane. At the upper end of the head 3, on one side thereof, are lugs or perforated ears 5 which receive a pintle 6 which also passes through similar mating lugs or ears 7 on a ring 8, the ring being thereby pivotally or hingedly mounted upon the head to be

supported thereby and swung at will into various angular positions in a vertical plane. Within the body of the head is formed a recess or cavity 9 opening through the top of the head and communicating with the lower end of said cavity is an arcuate passage 10 which extends through the head, and an arcuate rack 11 is mounted in the head to extend through said arcuate passage, the rack and the passage having the pintle 6 as their center. An operating shaft 12 is journaled 10 in the sides of the head and extends through the lower portion of the cavity 9, a pinion 13 being secured upon the shaft within the cavity and meshing with the rack 11, as will be understood upon reference to Figures 2 and 5, so that if the shaft be turned the rack will be caused to move endwise and thereby swing the ring 8 in a vertical plane. The shaft 12 is provided at one end with a crank or other suitable handle 14 and mounted within the head is a latch 15 20 which is adapted to engage the pinion 13 and hold the same against accidental turning so that normally the parts will be locked in the position in which they may be set. In the present instance, the latch is in the form of a spring-pressed pin or 25 rod having a knob or enlargement at its outer end and having its inner end arranged to engage between teeth of the pinion 13, as clearly shown in Figure 2, but any other suitable form of latch may be employed, if preferred. It will be understood that the latch is spring-pressed into engagement with the pinion and when the position of the parts is to be changed the latch is withdrawn by a pull exerted thereon in opposition to the spring.

35 The ring 8 is provided in its inner periphery with a series of seats in which are mounted rollers 16 which project somewhat beyond the inner periphery of the ring and engage in an annular groove 17 formed in the outer circumference 40 of an inner ring 18 which is disposed concentric with the outer ring, as shown clearly in Figures 2 and 3. The outer ring consequently serves as a support for the inner ring which may be readily turned about the common center of the 45 rings but cannot be readily detached therefrom and in order to facilitate assembling of the parts, it will be noted that the outer ring is split, as shown at 19, so that it may be readily brought into position about the inner ring, the ends of 50 the outer ring being constructed to overlap whereby they may receive securing bolts or screws, as will be understood upon reference to Figure 3. At diametrically opposite points on the inner circumference of the inner ring are mounted 55

bearing brackets 20 which receive the ends of a pivot rod 21. This pivot rod passes through a block 22 which is disposed midway the ends of the rod and is held against movement along the 5 rod by pins or studs 23 disposed against opposite sides of the block, as shown in Figure 3. Clamping bands 24 extend from a strap 25 and are preferably integral therewith, the strap being secured by a rivet or equivalent device 26 to one side of the block 22, as clearly shown in Figure 4 and to the opposite side of the block a sight bar 27 10 is secured by a rivet or the like 28. A machine gun 29 of any approved detail construction is inserted through and carried by the clamping bands 24 and the sight bar 27 is arranged parallel with the gun, as will be understood. It will be readily understood that the sight bar is close to the gun and the gun and the sight bar will always be pointed in the same direction and 15 to further guard against deviation in the relation of the sight bar to the gun, a bracket 30 is provided at one side of the block 22 and is secured to the gun and the sight bar so as to rigidly connect the same and cooperate with the rivet 28 to support the sight bar in the proper 20 relation to the gun. A search light 31 is mounted upon the block 22 in any convenient manner and is maintained in parallelism with the gun and the sight bar and is disposed adjacent the 25 sight bar, as will be understood.

When the gun is operated in daylight, the sight bar will be used for aiming the gun, but when used at night, the search light will be brought into use. The search light, of course, will be connected through proper electrical conductors with a battery or other source of electrical energy which may be mounted upon the pedestal or may be part of a generating plant at the location of the gun.

40 From the foregoing description, taken in connection with the accompanying drawings, it will be readily seen that I have provided a very simple mechanism whereby a gun and sighting elements may be easily manipulated and will be firmly supported in all positions. By properly 45 rotating the pinion 13, the rack 11 will be caused to turn the ring 8 to any desired position and the gun and parts mounted in said ring will, of course, be correspondingly adjusted. At the 50 same time, the gun may be turned pivotally about the rod 21 so that it may be quickly turned upon an approaching aircraft. The movement about the center 21 is obviously limited as the firing end of the gun will be brought into contact with the head 3, as shown by the dotted lines in Figure 1, so that when it becomes necessary to fire 55 at an aircraft which is directly overhead the shaft 12 must be turned so as to effect adjustment through movement of the rack 11, as will be understood. When the gun is to be fired at an aircraft which is directly approaching the gun, it has been found to be desirable to turn the gun upon its side with respect to the normal position of the sight bar and this adjustment is effected 60 by merely rotating the inner ring 18 within the outer supporting ring 8. While a firm and readily adjusted support for the gun and sighting elements is provided, the parts are so disposed

that there is no interference whatever with the firing of the gun and it may be manipulated as rapidly as a gun mounted in a fixed support.

Having thus described the invention, I claim:

1. In apparatus for the purpose stated, a fixed support, an outer ring pivoted upon the support to extend vertically above the same or laterally therefrom and having spaced seats in its inner circumference, rollers mounted in said seats, an inner ring having an annular groove in its outer 10 circumference engaging said rollers whereby the inner ring will be held against separation from the outer ring and may rotate therein, a pivot rod mounted diametrically within the inner ring, and a gun carried by said rod to rock about the 15 same.

2. In apparatus for the purpose stated, a fixed pedestal, a head swiveled in the upper end of the pedestal and having a cavity opening through its upper end and an arcuate passage extending 20 through said head and communicating with the lower end of said cavity, a ring pivotally mounted upon the upper end of the head to extend vertically over the head or horizontally at the side thereof, a gun carried by the ring, an arcuate 25 rack bar extending from the ring through the arcuate passage in the head, a pinion in the lower end of the cavity in the head meshing with said rack bar, means on the head for rotating said pinion, and means mounted in the head for holding 30 said pinion against rotation at will.

3. In apparatus for the purpose stated, a stationary pedestal, a head mounted on the pedestal for rotation about a vertical axis, a ring pivoted at a point on its outer circumference upon the 35 side of the head at the upper end of the head to extend vertically above the head or horizontally at the side of the same, means for securing said ring in a set position, a second ring disposed concentrically within the first-mentioned ring and 40 held therein for rotation about the common axis of the two rings, a rod secured diametrically within the second ring and a gun mounted on said rod to rock about the same and extending through the rings at a right angle to said rod and at one 45 side of the same.

4. In apparatus for the purpose stated, a fixed support, a pair of concentric rings, the outer ring being pivoted on the support to extend above the same or laterally therefrom, means 50 rotatably mounting the inner ring within the outer ring, and a gun mounted pivotally through the inner ring eccentrically to a diameter thereof and adapted to rock about the said diameter 55 thereof.

5. In apparatus for the purpose stated, a support, an outer ring pivoted to said support, an inner ring rotatably mounted in the outer ring concentric thereto, a pivot rod mounted in said ring on a diameter thereof, a block midway the 60 length of said rod to rock thereon, means for preventing endwise movement of said block along the rod, and a gun carried by said block at one side of the pivot rod and extending at a right 65 angle to the pivot rod.

WILLIAM W. FERGUS. [L. S.]
